PAUL E. JERTBERG, OF GLENDALE, CALIFORNIA

AUTOMATIC TANK SIPHON

Application filed May 6, 1929. Serial No. 360,723.

This invention relates to an automatic siphon used in conjunction with tanks for draining the latter. Such tanks are commonly employed to flush urinals. The invention is applicable to any device wherein a tank or receptacle receives a liquid and is drained by a siphon when a predetermined liquid level is reached in the tank.

Automatic tanks for urinals should be arranged to operate at equal intervals of time. If a liquid level actuator is employed to control draining of the tank, then the time interval may be regulated by the rate of filling of the tank. It has been common practice to employ float actuated valve mechanisms and tilting tanks for this purpose and also siphons dependent on the rate of flow of the liquid into the tank. The present invention relates to a siphon which is started into action when a predetermined liquid level is reached in the tank and is not dependent on the rate of flow into the tank.

The objects of this invention are to provide an automatic tank having any or all of the following features: no moving parts; an automatic siphon of novel character; and an automatic siphon which will permit a slow filling of the tank.

These objects together with other objects and corresponding accomplishments are obtained by means of the embodiments of my invention illustrated in the accompanying drawings, in which:—

Fig. 1 is a section through an automatic flush tank equipped with my improved siphon shown in elevation; Fig. 2 is a section as seen on the line 2—2 of Fig. 1; Fig. 3 is a section as seen on the line 3—3 of Fig. 1; and Fig. 4 is a diagraphic view to illustrate the operation of the siphon.

Referring more particularly to the drawing, a tank 5 is provided with an outlet coupling 6 adapted to be secured to a flush pipe. A filling pipe line 7 has a leg 8 extending close to the bottom of the tank and a control valve 9 is provided for regulating the rate of filling of the tank. Connected to the outlet coupling is a siphon consisting of a discharge limb 10 and a receiving limb 11. The limb 11 is extended upwardly adjacent its

inlet end to form a limb 12 which joins with a downwardly extending limb 13. Limbs 10 and 11 form the main siphon marked A and limbs 12 and 13 form an auxiliary siphon marked B. Limbs 11 and 12 form a liquid trap C. For the purpose of making the siphon compact, the auxiliary siphon has its limbs in a plane at right angles to the plane of the main siphon.

A starting tube of siphon form is connected to the top of the curve in auxiliary siphon B, there being a branch 14 extending downwardly and connected to a branch 15 which has at its receiving end a curve leading to a downwardly extending branch 16 which is disposed in the bore of the outlet coupling. The starting tube is preferably a capillary tube with an intermediate portion 15 of enlarged diameter so that it has substantially no capillary action in that portion. An inlet port 17 of small cross sectional area is formed in the receiving limb 15 for communication of the limb with the liquid in the tank.

Referring to Fig. 4, the operation is as follows: Liquid enters the tank through the filling tube 8 at a rate dependent upon the opening of valve 9. The liquid rises in limb 13 and overflows into limb 12, passing into the trap C thereby trapping air in the curve B. The level of the liquid in limb 13 will be equal to the level of liquid in the tank less the air pressure of the entrapped air in curve B. The pressure of the air in curve B will be that equal to the difference in levels of the liquid in the limbs of trap C. Thus, the column of liquid in limb 13 plus the difference of levels in the limbs of trap C will be equal to the height of the liquid in the tank. The level of the liquid in limb 11 will thus be below the level of liquid in the tank. However, as the level of liquid in the tank is increased, the level of the liquid in limb 11 increases and eventually will reach the bottom of curve A. Liquid will enter port 17 in the air eduction tube and a trap will be formed at the lower curve, the pressure exerted being sufficient to seal the port 17 against the discharge of air as the pressure at the port is equal to the level of liquid in

the tank less the height of the port 17 above the bottom of the tank. This difference in levels is such that the pressure is greater than that in the pressure air trapped in curve B. 5 At the same time liquid will rise in limb 15. Finally it will reach the upper curve in the eduction tube and flow over into discharge limb 16 and a siphoning action will be started which will cause the eduction of air from 10 curve B so that a siphonic action will be started in the main siphon and the tank will be emptied. In order to prevent liquid from overflowing from receiving limb 15 to discharge limb 16 without starting a siphonic 15 action, I have provided a capillary tube. To prevent the capillary action from causing the column in the receiving limb 15 from rising to the curve and starting the siphonic action before it is desired, I have enlarged the 20 bore of receiving limb 15 to overcome the capillary action. This also does away with the possibility of liquid in limb 16, acting as a plug and starting a siphonic action before it is desired.

25 What I claim is:—

1. The combination of a receptacle for liquid; a double curve siphon having one curve at the discharge end and the other at the receiving end; the latter curve forming an air trap; an air eduction tube connected to the curve at the air trap and ranging downwardly, thence upwardly to form a receiving limb of a siphon and thence downwardly to form a discharge limb, and a port of 30 relatively small area in the receiving limb of the last named siphon, said port being in communication with the liquid in said receptacle.

2. The combination of a receptacle for liquid; a double curve siphon having one curve at the discharge end and the other at the receiving end; the latter curve forming an air trap; an air eduction capillary tube connected to the curve at the air trap and ranging downwardly, thence upwardly to form a receiving limb of a siphon and thence downwardly to form a discharge limb, and a port of 45 relatively small area in the receiving limb of the last named siphon, said port being in communication with the liquid in said receptacle.

3. The combination of a receptacle for liquid; a double curve siphon having one curve at the discharge end and the other at the receiving end; the latter curve forming an air trap; an air eduction capillary tube connected to the curve at the air trap and ranging downwardly, thence upwardly to form a receiving limb of a siphon and thence 55 downwardly to form a discharge limb, the receiving limb being of enlarged bore to decrease capillary action, a port of relatively small area in the receiving limb of the last named siphon, said port being in communication with the liquid in said receptacle.

4. The combination of a tank for liquid; a double curve siphon disposed therein having one curve at the discharge end and the other at the receiving end, the latter curve forming an air trap; an air eduction tube connected to the curve at the air trap and disposed within said tank, said tubing ranging downwardly, thence upwardly to form a receiving limb of a siphon and thence downwardly forming a discharge limb, a port of 70 relatively small area in the receiving end of the last named siphon. 75

5. The combination of a tank for liquid, a double curve siphon having one curve at the discharge end and the other at the receiving 80 end, the latter curve forming an air trap; an air eduction tube connected to the curve at the air trap and disposed within said receptacle, said tube being a capillary tube and ranging downwardly, thence upwardly to 85 form a receiving limb of a siphon and thence downwardly forming a discharge limb, a port of relatively small area in the receiving limb of the last named siphon.

6. The combination of a tank for liquid; a double curve siphon disposed within said tank having a curve at the discharge end and the other curve at the receiving end, the latter curve forming an air trap; an air eduction capillary tube in said tank connected to the curve at the air trap and ranging downwardly, thence upwardly to form a receiving limb of a siphon and thence downwardly to form a discharge limb of a siphon, the receiving limb being of enlarged bore to decrease 95 capillary action, and a port of relatively small area in the receiving limb of the last mentioned siphon. 100

7. The combination of a double curve siphon having one curve at the discharge end 105 and the other at the receiving end, the latter curve forming an air trap; an air eduction tube connected to the curve at the air trap and ranging downwardly, thence upwardly to form a receiving limb of a siphon and thence downwardly to form a discharge limb, and a port of relatively small area in the receiving limb of the last named siphon. 110

8. The combination of a double curve siphon having one curve at the discharge end 115 and the other at the receiving end, the latter curve forming an air trap; an air eduction capillary tube connected to the curve at the air trap and ranging downwardly, thence upwardly to form a receiving limb of a siphon 120 and thence downwardly to form a discharge limb, and a port of relatively small area in the receiving limb of the last named siphon.

9. The combination of a double curve siphon having one curve at the discharge end 125 and the other at the receiving end; the latter curve forming an air trap; an air eduction capillary tube connected to the curve at the air trap and ranging downwardly, thence upwardly to form a receiving limb of a siphon 130

and thence downwardly to form a discharge limb, the receiving limb being of enlarged bore to decrease capillary action, and a port of relatively small area in the receiving end of the last named siphon.

5 In witness that I claim the foregoing I have hereunto subscribed my name this 27th day of April, 1929.
